UNITED STATES PATENT OFFICE.

GEORGE E. GARBOW, OF PIERSON, MICHIGAN.

POTATO-SEED-CUTTING MACHINE.

1,267,397.

Specification of Letters Patent. Patented May 28, 1918.

Application filed September 17, 1917. Serial No. 191,816.

To all whom it may concern:

Be it known that I, GEORGE E. GARBOW, a citizen of the United States, residing at Pier-
son, in the county of Montcalm and State of
Michigan, have invented certain new and
useful Improvements in Potato-Seed-Cut-
ting Machines, of which the following is a
specification.

This invention relates to an improved potato seeding machine and the principal object of the invention is to provide a machine so constructed that the potatoes may be carried up an endless belt into operative engagement with rotating cutting knives and sliced into sections, the sections being then brought into engagement with the removing plates serving to disconnect the sections from the belt.

Another object of the invention is to so construct this belt that the potato engaging pins thereof will be so positioned or inclined that the potatoes will not be moved out of engagement therewith when cut and will be so inclined that when the potatoes engage the removing plates, they may be easily disconnected from the penetrating pins.

Another object of the invention is to so construct this machine that if desired, the removing plates may be turned from an operative position thus permitting one plate to be left in an operative position to remove one section of the potato from the belt and permit the remaining section of the potato to be returned to the operator and again connected with the belt for cutting.

Another object of the invention is to so construct this machine that one person may operate the same if so desired.

This invention is illustrated in the accompanying drawings, wherein:—

Figure 1 is a view showing the improved potato seeding machine in side elevation,

Fig. 2 is a top plan view of the improved machine with a small portion of the travel-
ing belt or apron broken away,

Fig. 3 is a view showing the improved machine in side elevation looking from the opposite side of the machine from the view shown in Fig. 1,

Fig. 4 is a fragmentary longitudinal sectional view through the improved machine, and

Fig. 5 is a perspective view showing two of the removing plates.

The improved machine is provided with a

base 10 having standards 11 and 12 extending therefrom and carrying side bars 13, the base, standards and side bars forming a frame. The apron or belt 14 will be formed of flexible material such as canvas, leather or any other suitable material and carries sprocket chains 15 passing about the sprocket wheels 16 mounted upon the upper and lower shafts 17 and 18. A table or supporting board 19 will be placed beneath the upper flight of this apron thus providing a support and preventing sagging of the upper flight when the machine is in use. In addition to the sprocket carrying shafts 17 and 18, there has been provided shafts 20 and 21 extending through the side bars 13, the shaft 21 carrying a gear 22 meshing with a gear 23 carried by the shaft 20 and the shaft 20 carrying a second gear 24 meshing with the gear 25 of the shafts 17. It will thus be seen that when the shaft 21 is rotated through the medium of the handle 26 carried by gear 27 rotary movement will be transmitted to the shaft 17 and further that rotary movement will be transmitted to the shaft 28 through the medium of the gear 29 mounted thereon and meshing with the gear 27. This shaft 28 carries a fly wheel 30 and is provided intermediate its length with cutting disks 31 extending in operative relation to the apron 14. The apron 14 carries rows of pins 32 which extend at an angle as shown in Figs. 1, 3 and 4 so that the pins of the upper flight of this apron will be inclined toward the lower end of the frame. These pins pass upon opposite sides of the cutting knives and it will be readily seen that when in operation, a potato placed upon the pins will be moved upwardly and carried past the cutting disks with the cutting disks cutting the potato into sections. By having the pins inclined as shown, the potato may be cut without danger of being moved off of the pins through engagement with the cutting disks and further by having the pins inclined as shown, the sections of the potato may be easily moved from the pins when the pins pass through the cutouts 33 of the removing plates 34. These removing plates will be pivotally mounted upon a rod 35 and will be limited in their swinging movement in one direction by the cross bar or rod 36 so that they will be prevented from engaging the apron. It will be further noted that the plates will be provided with

extensions 34' to engage the rod 36 and limit the swinging of the plates when moved upwardly.

The potatoes may be placed upon the pins 5 with one hand and the driving shaft 21 rotated through the medium of the handle 26 engaged by the second hand or one person can turn the driving shaft and another can feed the potatoes upon the apron. The potatoes 10 will be placed upon the pins and will be carried upwardly past the cutting knives which knives will cut them into sections. The sections will be carried upwardly to the end of the machine and when engaging 15 the plates will be removed from the pins and will drop into a suitable receptacle. If a large potato is to be cut and it is desired to cut the potato more than once, it will be placed upon the pins and one of the removing 20 plates for the particular set of pins will be swung backwardly out of the way. This will permit the larger section of the potato to be passed down and be carried along the lower flight of the apron while the smaller 25 section will be removed by the plates in an operative position and will drop into the receptacle. The larger section can be removed from the apron when it reaches the lower end of the frame and it can be put in 30 place so that the section will be again cut. If so desired, large potatoes could be cut on one side of the machine and smaller ones on the opposite side thus permitting the large potatoes to be put in place on one side and 35 when cut the larger sections removed and put in place upon the opposite side of the machine so that both sections would then be removed when the larger section is cut.

There has therefore been provided a potato 40 seed cutting machine which will be very convenient for use and which will be very efficient in operation since the potatoes can be quickly and easily cut. It will be further noted that by providing the board 45 or table 19 a good support will be provided for the potato thus preventing sagging of the upper flight of the apron and further insuring a good cut when the potato passes beneath the cutting knife.

50 What is claimed is:—

1. A potato seed cutter comprising a frame including a base, forward and rear standards extending from the base, side bars connected with the standards and positioned at 55 an incline, an endless apron movably mounted between the side bars, potato penetrating and carrying pins extending from the apron, cutting means positioned above the upper flight of the apron and in operative relation to the potato carrying pins, and means for engaging cut sections of potato and removing the same from the pins.

60 2. A potato cutting machine comprising a frame including standards, side bars carried 65 by the standards and extending at an incline,

an endless apron movably mounted between the side bars; penetrating pins extending from the apron in longitudinally extending rows with the pins of the upper flight of the apron positioned at an incline toward 70 the lower ends of the side bars, cutting means rotatably mounted above the apron in operative relation to the rows of penetrating pins, means for driving the cutting means and imparting movement to the 75 apron, and means for removing sliced sections of potato from the penetrating pins.

3. A potato seed cutting machine comprising a frame, an endless apron movably mounted in said frame, penetrating pins extending from the apron and inclined toward the end thereof, cutting means carried by the frame and positioned in operative relation to the apron and pins carried thereby, and means carried by the frame for removing sliced potato sections from the pins. 80

4. A slicing machine of the character described comprising a frame including side bars, upper and lower shafts extending between the side bars, sprockets carried by the shafts, an endless apron, sprocket chains carried by the apron and passing about the sprocket wheels, carriers carried by the apron, a driven shaft rotatably mounted above the apron and carrying cutting knives 90 extending in operative relation to the carrying elements of the apron, means for imparting rotary movement to the knife carrying shaft and to one of the first mentioned shafts, and means for removing sliced articles from the carrying element of the apron. 95

5. A slicing machine comprising a conveyer frame including side bars and standards for the side bars with one set of standards extending above the side bars, upper 105 and lower shafts extending between the side bars, sprocket wheels carried by the upper and lower shafts, an endless conveyer belt in the conveyer frame, sprocket chains carried by the belt and engaging the sprocket 110 wheels, a knife carrying shaft rotatably supported by the standards extending above the side bars with the knives of the knife carrying shaft positioned in operative relation to the conveyer belt, a driving shaft, 115 means for imparting rotary movement from the driving shaft to the knife carrying shaft, and means for imparting rotary movement from the driving shaft to one of the first mentioned shafts. 120

6. A slicing machine of the character described comprising a conveyer frame, a conveyer apron movably mounted in the frame and having upper and lower flights, carrying pins extending from the apron and extending longitudinally of the apron, removing plates pivotally mounted and having their free end portions extending toward the apron and provided with cutouts permitting passage of the pins when the plates 125 130

are in an operative position, and means for supporting the plates in operative position and out of contact with the apron.

7. A potato seed cutter comprising a frame, an endless apron movably mounted in the frame, potato penetrating and carrying pins extending from the apron, cutting means positioned above the apron in an operative relation to the potato carrying pins, and means for engaging cut sections of a potato and removing the same from the pins.

8. A slicing machine of the character described comprising a conveyer frame, an endless conveyer apron movably mounted

in the frame, carrying pins extending from the apron, cutting knives mounted in operative relation to the apron, and removing plates mounted in operative relation to the apron and having their free end portions 20 extending toward the apron and provided with cutouts permitting passage of the pins when the plates are in an operative position.

In testimony whereof I affix my signature in presence of two witnesses.

GEORGE E. GARBOW.
